UNITED STATES PATENT OFFICE

ARTHUR FRIEDMAN, OF CLEVELAND, OHIO, ASSIGNOR TO THE CLEVELAND HEATER COMPANY, OF CLEVELAND, OHIO, A CORPORATION OF OHIO

REINFORCED CIRCULATING COIL

Application filed February 27, 1928. Serial No. 257,222.

This invention relates to improvements in gas burning liquid heaters and in particular to the circulating coils used in gas burning domestic water heaters.

5 It has for its object the provision of a water heating circulating coil that is inexpensive and easy to manufacture, and that is more durable than the ordinary type of circulating coil, and that is re-enforced and protected 10 against the destructive action of the condensation formed thereon from the products of combustion of the gaseous fuels commonly used in gas burning water heaters.

My invention in general consists in the 15 provision of a double section of tubing which constitutes that portion of the heater coil terminating in the lower coil coupling. This re-enforcement in general extends about three or four inches from the coupling and is placed 20 three for the purpose of strengthening the recoil, at this point, against the corrosive action of the liquids which condense on the heater coils and eventually find their way to the lowest portion of the heater coils collecting 25 at the junction of the coils and the coupling.

In copper heater coils of the ordinary type there is a decided tendency for the coils to fail at the point where they enter the lower 30 coupling member. This failure of the coils is due to the disintegration of the copper from which the coils are made, and is usually accompanied by the formation of copper sulphate or other decomposition compounds at 35 the point of failure at the coil. It is common knowledge that many commercial gases, particularly manufactured gas, upon burning give off an oxide of sulphur as well as water vapor.

40 The accepted theory of this phenomena observed in gas fired water heaters is that the condensation of water vapor which takes place on the heater coils, causes the formation of sulphurous acid by combining with the sulphur dioxide given off by the burning gas.

As the weak sulphurous acid thus formed on the heater coils runs to the bottom of the coils, a certain amount of it is converted into sulphuric acid, by reason of coming in contact with what copper oxide may be present 50 on the heater coils.

The dilute acids thus formed collect at the lowermost point of the coils, which is where they enter the bottom coil coupling. At this point there is apt to be present considerable 55 copper oxide if it is a brazed joint. The oxide referred to is present as a result of the action of the gas flame used in the brazing operation.

Furthermore, the copper tubing at the 60 brazed joint is somewhat weakened, due to the heat applied in brazing, which causes some oxidation as well as annealing, both of which are apt to leave this portion of the copper tubing in a condition in which it is 65 more susceptible to the corrosive action of sulphuric acid than the other portions of the tube.

Disregarding for the moment, the type of 70 joint between the tubing and the coupling, whether it be a brazed joint or a union coupling, it is apparent that a part of the aforementioned liquids, condensed from the products of combustion of the gaseous fuel, come to rest at the junction of the coupling and the 75 coils.

At this junction point, which is in close proximity to the heater burner, the condensation products are further concentrated by 80 direct action of the flame and evaporation of excess water in the acid solutions producing concentrated sulphuric acid, which readily combines with the copper of the heater coil.

It is upon this theory, which is supported 85 by the presence of copper sulphate at the junction of the coupling and the tubing, after the heater has been in use for some time, that the common cause of failure of the copper coils of water heaters is accounted for.

The formation of scale and liming of the 90

interior of the heater coils accelerates their deterioration. Under these conditions, when in operation, the heater coils are kept at a much higher degree of temperature, due to the low thermal conductivity of the fouled tubing, and in addition to being more rapidly disintegrated by sulphuric acid, the coils are also oxidized by the direct action of the burner flame.

10 The primary object of this invention is to re-enforce that part of the heater coil which is most apt to be attacked by the aforementioned condensation products of combustion.

15 This result is accomplished in my improved coil by the provision of an extra section of tubing over the last few inches of the lower portion of the coils. By this arrangement the coil is materially strengthened at this 20 point and its useful life should be materially lengthened thereby.

This invention is particularly useful in water heaters in which the ends of the circulating coil are brazed in the coil coupling member, as the coils are somewhat weakened by this operation, due to the high heat which is applied to them, and to the action of the fluxes which are used in brazing.

In the accompanying drawings Fig. 1 20 shows a front elevation, partly in section, of a water heater constructed in accordance with, and adapted for use in practising my invention. Fig. 2 is a plan elevational view 25 partly in section of the coil coupling and the coil re-enforcing member.

Referring to the drawings, the reference numeral 1, indicates the heater casing or jacket of a conventional gas fired domestic water heater. This casing provides a housing for the copper circulating coils 2 which are adapted to be put into communication with a storage vessel or tank by means of the lower and upper union-connections 3 and 4, respectively.

45 Means for applying heat to the coils is provided for by the gas burner 5, which is mounted on an air and gas mixing tube 7, of the Venturi type. The burner 5 is positioned below the coils in the lower portion of 50 the heater jacket. A gas cock 8 is mounted at the inlet end of the mixing tube 7, and is adapted to be connected to a source of gas supply.

The heater coils 2 are provided at their 55 lower extremities with a short re-enforcing section 9, of tubing which is adapted to be secured in the coupling member 6 by any suitable method such as brazing. The joint 10 between the overlapping re-enforcing section and the coil to which it is applied may also be effected by brazing.

The re-enforcing sections 9 may be formed independently of the coils 2 and then slipped over the coils before the brazing operation, or they may be formed by the same operation

that is used in forming coils 2. The sections 9, if so desired, may be made of heavier gauge tubing than the coils 2. The coils 2 may be made to terminate a short distance from the joint 10 instead of extending to the end of the re-enforcing sections 9. As shown in the drawings, the joint 10 of the coil sections 2 and 9 joins these portions of the coil to each other with a smoothly bevelled joint so that there will be no tendency for the collection of condensate at this point.

It is apparent from the foregoing that this type of re-enforcement will materially lengthen the life of the coils and protect them against sulphation, as well as, oxidation by the flame of the burner 5, which is apt to happen in case the interior of the coils becomes covered with scale.

It is apparent that my improved heater coil could be used in conjunction with oil burning water heaters as well as gas burning water heaters and that it could be used to advantage in the heating of liquids other than water, where said coils are subjected to treatment similar to that which they receive in gas fired water heaters.

Furthermore, it is to be understood that the particular forms of apparatus shown and described, and the particular procedure set forth, are presented for purpose of explanation and illustration and that various modifications of said apparatus and procedure can be made without departing from my invention as defined in the appended claims.

Having described my invention, I claim:

1. In a water heater, a vertically arranged tubular circulating coil, a coupling member for the lower end of said coil, heating means located below said coil, and coil re-enforcing means comprising a relatively short section of tubing providing a protective sheath that encompasses the lower end portion of said coil to protect said coil at the point where it enters said coupling from the corrosive action of condensate deposited on said coil and collected at this point.

2. In a liquid heater, a vertically arranged tubular circulating coil, means for supplying heat to said coil, a relatively short re-enforcing sleeve positioned on the lower end portion of said coil to protect the same against the corrosive action of condensate collected on the coil at this point, and a coupling member connected in fluid tight relation to the end portion of said sleeve and coil.

3. In a liquid heater, a vertically arranged tubular circulating coil terminating in a double walled portion of less than $\frac{1}{4}$ of a coil turn at its lower extremity, means for supplying heat to said coil, and a coupling member brazed to the lower end of said coil, said double walled portion of the coil being adapted to strengthen the coil against the

corrosive action of condensate collected at the junction of said coupling and coil.

4. In a liquid heater, means for supplying heat thereto, a vertically arranged tubular circulating coil formed from a piece of metal tubing, a protecting sleeve formed from a relatively short section of tubing of similar material and of larger diameter than the coil tubing fitted over the lower end portion 5 of the tubing of said coil, and a coupling member receiving and brazed to the end of said coil and sleeve, said sleeve strengthening the junction of said coupling and coil.

In testimony whereof I affix my signature.

15. ARTHUR FRIEDMAN.
